[57] **ABSTRACT**

The invention relates to a method and device for facilitating the separation from a plurality of edge-aligned parallel cards, such as edge-notched cards, those cards which are to be removed therefrom. To facilitate separation of cards from a group from which they are removable, a cylindrical brush is rotated in contact with aligned edges of a plurality of cards which support one another in substantially vertical orientation. A suitable brush comprises an arbor having at least one cylindrical segment which includes one or more brush elements. A card separating device includes means to move from a plurality of edge-aligned cards certain "selected" cards from the remaining, "rejected," cards thus effecting a separation of selected cards. The brush according to the present invention facilitates this separating motion. The brush bristles contact all of the edge-aligned cards and are sufficiently resilient to deflect on contacting a stationary card and sufficiently stiff to enter into the space between adjacent cards to facilitate card separation.

BRUSH FOR ASSISTING IN SEPARATION OF SHEETS

This invention is a continuation-in-part of our earlier application Ser. No. 811,826, filed Apr. 1, 1969, now U.S. Pat. No. 3,586,166, issued June 22, 1971.

BACKGROUND OF THE INVENTION

This invention relates to a method and device for facilitating the separation from a plurality of edge-aligned, vertically oriented cards, such as edge-notched cards, those cards which are to be removed therefrom. In another aspect, the invention relates to card sorting and in particular, it relates to the sorting of vertically oriented, edge-aligned, edge-notched cards.

Numerous arrangements of this type are presently known for sorting edge-notched cards. These range from simple mechanical elongated rod devices to complex automatic machines. A typical and preferred device of this type is disclosed in our earlier pending application Ser. No. 811,826, herein incorporated by reference. In these machines, a plurality of edge-notched cards are stored in edge alignment and with adjacent cards supporting one another in vertical orientation. The machine is utilized to select certain cards determined by the particular location of a notch or notches along a notched edge. Due to electrostatic and frictional forces between the adjacent cards, the machines usually include a device to facilitate separation of the selected cards from the plurality of cards in the machine. Known devices include air streams, vibrators and the like. In any device of this type, the separation of the cards is critical. For example, if the cards are not completely separated, only some of the data which is sought will be obtained. Thus, it is critical in machines of this type that the cards desired to be separated are easily separated from the bulk of the cards in the machine. It is therefore an object of the present invention to provide a method and device for facilitating the separation from a plurality of parallel, edge-aligned, vertically oriented cards, those cards which are to be removed therefrom.

SUMMARY OF THE INVENTION

The foregoing and other objects are achieved according to the present invention by providing in a device for separating selected cards from a plurality of edge-aligned, vertically oriented, cards including at least one storage bay for holding a plurality of edge-aligned cards with adjacent cards supporting one another in vertical orientation, means for moving certain selected cards relative to the remaining, rejected, cards to effect separation thereof; the improvement wherein said device includes brush means to facilitate separation of said sheets, said brush means comprising a brush member positioned adjacent to the aligned edges of said sheets with the bristles of said brush member being engageable with the aligned edges of the cards in said bay, and means to move the brush bristles in engagement with said aligned edges to facilitate sheet separation, said bristles being sufficiently flexible to deflect upon striking said card edges and sufficiently stiff to enter into the space between adjacent cards to pass between adjacent cards to facilitate separation thereof. Separation of the cards is facilitated according to the invention by contacting the edges of edge-

aligned cards having adjacent cards supporting one another in vertical orientation with a moving brush, said brush including bristles which are sufficiently flexible to deflect upon striking said edges and sufficiently stiff to pass into the space between adjacent sheets to pass between adjacent cards to facilitate separation thereof.

DETAILED DESCRIPTION OF THE PREFERRED EMBODIMENT

There follows a detailed description of a preferred embodiment of the invention, together with accompanying drawings. However, it is to be understood that the detailed description and accompanying drawings are provided solely for the purpose of illustrating a preferred embodiment and that the invention is capable of numerous modifications and variations apparent to those skilled in the art without departing from the spirit and scope of the invention.

FIG. 1 is a diagrammatic elevation view of a portion of a card sorting device employing a rotating brush device according to the present invention;

FIG. 2 is a perspective view of a portion of a cylindrical surface of a brush according to the invention;

FIG. 3 is a plan view of a portion of a cylindrical surface of a brush according to the invention;

FIG. 4 is a diagrammatic elevation view of a brush device according to the present invention; and

FIG. 5 is a series of curves showing rise motion as a function of time for various brush arrangements.

With reference to FIG. 1, a card sorting device 1 comprises a housing 2 and a plurality of edge-aligned parallel cards 3. The device illustrated corresponds to that shown in our earlier U.S. Pat. application Ser. No. 811,826 and includes means to select cards and to remove those selected cards from the machine. Full details with respect to construction and operation of the card sorting machine will be found in that application which is incorporated herein by reference. Two brush devices, 4 and 5, according to the present invention are provided in the card sorting device and will be described in detail hereinafter. These brushes each comprise an arbor rotated by means of a motor 6 by means of an idler pulley 7 and drive belts 8, 9 and 10.

Each brush arbor is cylindrical and the surface and arrangement of the brush bristles are shown in FIG. 2. The brush arbor surface comprises at least one segment, each of which conveniently corresponds to a card holding bay in the device, three being shown in FIG. 3. Each segment comprises a plurality of brush elements 10 circumferentially spaced a distance X from one another. The distance X is conveniently expressed in degrees and the brush elements are preferably equally spaced around the segment, six equally circumferentially spaced brush elements being shown in FIG. 2. While the number of circumferentially spaced brush elements in a segment can vary widely, there are preferably at least three. As mentioned, a brush may comprise more than one segment, and, in that event, the segments may comprise physically separate zones or areas on a continuous cylindrical brush surface having brush elements around the surface thereof. In either event, each segment according to the invention may include a plurality of brush elements circumferentially spaced about the cylindrical surface thereof.

Each brush element comprises a plurality of conventional bristles, either natural or synthetic, which may be secured to the brush arbor in any conventional manner, such as by an adhesive backing. The bristles extend outwardly, preferably radially, of the cylindrical brush arbor.

The bristles are selected to be sufficiently flexible to deflect upon striking the aligned edges of the cards and sufficiently stiff to pass into the space between adjacent cards and to pass between adjacent cards to facilitate separation thereof. The required flexibility and stiffness depend, of course, on the spacing and thickness of the cards. However, the spacing and size of the cards is conventional. The cards are loosely compacted in vertical alignment in such a manner that adjacent cards support one another in vertical alignment. The cards are loosely compacted such that cards can move relative to one another without excessive friction. The cards themselves are conventional and are usually of the order of from 5 to 100 mils in thickness. Preferably, the cards are of the order of 5 to 20 mils in thickness to conserve space, and the most widely used cards are approximately 7 mils in thickness.

In order to minimize inter card frictional forces which impede card separation, the cards are provided in vertical orientation prior to movement of the selected cards relative to the remaining, rejected cards. The cards are usually provided vertically in a bay defined by side walls which may be adjustable to vary the bay width to accommodate a larger or smaller number of cards in a bay. The side walls may be resiliently urged against the cards an amount sufficient to hold the cards loosely compacted in vertical orientation. More preferably, however, the side walls are in fixed position during card selection, the number of cards between the bay being such that the cards are only loosely compacted. In either event, adjacent cards support one another in vertical orientation and the cards are loosely compacted such that the cards occupy from about 50 to 85 percent, more preferably 70 to 80 percent, of the space between adjacent side walls, the remainder being free space. The bristles preferably have a diameter larger than the card thickness.

The bristles can be disposed on the brush element in several ways. In general, it is preferred to arrange the bristles into a plurality of separate elements on the brush so that a vibrating action, as well as a brushing action, will be imparted to the cards on motion of the brush adjacent to the aligned card edges. The brush is moved such that the individual bristles move in a plane substantially parallel to the cards. This is conveniently achieved by providing a rotatable brush arbor extending transverse to the aligned card edges with brush bristles extending radially outward to contact the cards on rotation of the brush arbor.

The bristles are preferably arranged on the brush in such a manner that at any given moment when the brush is moving with its bristles in contact with the aligned card edges, not all of the card edges are contacted. Thus, the bristles are preferably provided in a spiral pattern on a cylindrical brush arbor. The spiral pattern may be continuous, as shown in FIG. 3, or discontinuous as shown in FIG. 2. By providing the bristles in this winding manner, motion of the brush causes a riffling action which has been found to be very effective in separating the cards. Where the brush ele-

ments are discontinuous, for example, when they are circumferentially spaced about the periphery of a cylindrical brush arbor as shown in FIG. 2, a vibrating action is superimposed on the riffling action and the combined riffling-vibrating action has been found to be remarkably efficient in separating cards. A preferred form of brush will now be described in connection with FIGS. 2, 4 and 5.

The brush arbor 12 is cylindrical (FIG. 4) and conveniently includes one or more segments, three being illustrated in FIG. 2, each segment conveniently corresponding to a bay in the card storage device. Thus, in this example, three bays defined by side walls are located in register with the three brush segments, the bristles in one segment contacting the aligned edges of the cards in the bay in registry therewith upon rotation of the brush arbor.

The brush elements 11 extend longitudinally of the segment preferably a distance Y less than the full length of the segment. In that event, each brush element overlaps an adjacent brush in that segment a distance Z. The brushes are conveniently staggered longitudinally of the arbor in a regular pattern, such as a helix, around the segment. Furthermore, the brush elements in a segment, taken together, at least extend fully from one side of the segment to the other. For example, as shown in FIG. 2, the brush elements are staggered with overlap such that four of the brushes taken together, extend from one side of the segment to the other.

Where the brush comprises a plurality of segments, it is preferred that the brushes of each segment are in circumferential alignment with all of the brush elements of each other segment as shown in FIG. 3. Thus, where six brush elements are provided in each segment equally spaced at 60° intervals about the periphery thereof, each brush of a segment is aligned longitudinally of the brush axis with a brush element of all other segments. As shown in FIG. 3, each brush in longitudinal alignment may also occupy a corresponding longitudinal position in its segment, but this is not necessary.

Upon rotation of the brush arbor, each bay segment rotates to contact the edge-aligned sheets to facilitate separation thereof. It is therefore preferred that the brush elements of a given segment are staggered to form a serpentine or zig-zag pattern extending across the segment at least once in each direction longitudinally of the brush as shown in FIG. 2.

Operation of the brush device will be explained with reference to FIG. 4. In this drawing, the brush arbor 12 is shown rotating counterclockwise as shown by arrow 23 in brushing engagement with the aligned edges of a plurality of cards 13, two cards R and S being shown. Originally, the top edges of all of the cards are aligned with edge 14 of Card R. Due to the action of selector bars 15 and 16, which cooperate with notches 17 and 18 in the bottom of card S, that card, hereinafter called the "selected" card, is free to move downwardly with respect to card R, hereinafter called the "rejected" card. While the rejected card also includes notches 19 and 20 in bottom edge 21 thereof, selector bars 15 and 16 engage lower edge 21 of the rejected card and thus hold the rejected card in its original position. The edge notches thus constitute a means of selecting certain

cards, such as cards containing certain information, corresponding to a code identified by the number and/or position of notches in an edge thereof such as notches 15 and 16. The use of edge notches for this purpose is widely known and reference is made to our copending application Ser. No. 811,826 for details of typical systems. In any event, a card sorting device includes means for storing a plurality of sheets parallel and in edge alignment. Usually the sheets are generally rectilinear and all four edges of the sheets are in alignment. The device also includes means to permit relative motion between selected and rejected cards to separate selected cards from the rejected cards. The present brush device operates as shown in FIGS. 1 and 4 to facilitate separation of the selected and rejected cards.

The cylindrical arbor of a brush device according to the present invention is located parallel with the aligned edges of a plurality of parallel and edge-aligned cards with its longitudinal axis generally transverse to a given edge of each individual card. The arbor is rotated about axle 22 in the direction of arrow 23 by a drive means, not shown in FIG. 4, which may comprise any conventional arrangement such as that shown in FIG. 1. The brush arbor may be biased downwardly towards the cards by any suitable means. In the embodiment shown, the drum is biased downwardly by its own weight in track 24 which comprises a slot in a support member 25 in which the axle is moveable. The brush arbor is moveable upwardly during rotation as in slot 24 of support 25.

It will be understood that as brush arbor 12 rotates, the circumferentially spaced brush elements of a given bay segment will intermittently contact the cards thus imparting a vibrating action. Each time a brush element strikes the cards, the bristles deflect and there is a tendency for the brush arbor to rise. In this embodiment of the invention, the mass of the bay segment is selected to be sufficient to ensure contact between the cards and each successive brush element, and the resiliency of the brush elements is preferably sufficient to impart a rise motion to the rotating brush segment upon contact between the brush element and the edge-aligned cards. The brush resiliency is preferably sufficient to overcome the kinetic energy of the rotating arbor such that a rise motion is imparted to the bay segment at operational speed. Thus, when an individual brush element contacts the cards, its resilience causes the brush arbor to rise in slot 24 thus causing the brush segment to rise. When the bristles leave the card, the segment falls downwardly until the next individual brush element strikes the cards when it will rise again. This motion is termed "rise motion" herein and its extent is termed "rise distance." Provided that the brush resilience substantially overcomes the momentum of the rotating brush segment, rise motion will be imparted to the segment.

The brush elements of the segment are also preferably offset longitudinally of the segment and, upon rotation of the brush, a riffling action is imparted to the cards. This riffling action, coupled with the vibrating effect caused by intermittent brush contact, provides excellent card separation according to the invention, particularly where the circumferential distance separating adjacent brush elements is such that the time interval between intermittent contacts at

operating speed is not greater than the time interval for a rise motion cycle.

Rise motion as a function of time for one revolution of a six brush element bay segment is shown in FIG. 5 for three situations. In all three situations, the resilience of the brush elements substantially overcomes the momentum of the brush segment thus imparting rise motion. In situation I, the spacing between successive brush elements in such that the time interval between successive brush contacts is the same as the time for rise motion. The curve shows the vertical motion of the brush axle during one revolution. The axle is pushed rapidly upwards a rise distance d_I and then falls by gravity a time equal to $\sqrt{2d}/386$. In the second situation, the brush spacing is greater such that rise motion a distance d_{II} is completely finished before the next brush contacts the cards. In the last situation, the spacing is such that the contact occurs prior to completion of a cycle of rise motion. The rise motion d_{III} in this instance is less than d_I , other things being equal. It has been found that arrangements I and III achieve excellent card separation according to the invention.

Brush elements were tested in a device described in detail in our earlier application.

A first brush device is constructed as shown in FIG. 2. Each segment contained 6 brush elements as shown, each brush element being about one-fourth of the width of the segment and having straight nylon bristles 10 mils in diameter. The thickness was chosen such that if each of the bristles occupied the space between a card, the cards would occupy the whole bay width of the machine corresponding to the width of the segment. A brush device operating in this manner having a circumferential brush element spacing as described in connection with schemes I and III of FIG. 5 achieves excellent card separation in about 1 second. With the same brush elements arranged according to scheme II of FIG. 5, effecting separation requires 4 seconds.

In another test, the brush elements of a segment were joined forming a continuous, herring bone pattern as shown in FIG. 3. Four continuous bristle elements, each being helically wound on a cylindrical arbor, two being wound in one sense and the other two being wound in the opposite sense, the pitch being equal to bay width as shown. The brush thus continuously contacts the cards and no rise motion was imparted. The time needed to effect comparable card separation is about 4 seconds. Thus, by circumferentially spacing the brush elements in accordance with the invention, card separating is greatly facilitated relative to continuous brushes or spaced brushes having other spacing arrangements.

In the embodiment shown in FIGS. 1 and 4, the brush is biased against the cards by its own weight. It will be understood however, that any resilient means for biasing the brush, such as a spring may be used. Thus, a spring can be utilized to bias the brush against side edges or even bottom edges, of the cards. In addition, a spring or the like biasing means may be utilized in a device according to the invention to lessen the effective mass of a brush by acting in a direction away from the cards. Thus, where the mass or momentum of the brush is referred to herein, it will be understood that it is the net mass, or net kinetic energy which is intended, taking into account the manner in which the brush is mounted, including biasing means.

The brush device is conveniently provided with means to hold the brush out of engagement with the cards when the brush is not in operation.

In a card sorting device as shown in our earlier application Ser. No. 811,826, the cards are conveniently stored in a plurality of separate bays. The brush device is thus conveniently provided with a like number of bay segments, each corresponding to a card bay. As mentioned above, the bay segments may be physically separated or may be merely areas on a continuous brush surface. In any event, the brush may comprise a single bay segment or a plurality thereof and, where a plurality of physically separated bay segments are provided, the rise motion of each may be independent of all others in which case longitudinal alignment of brushes in the elements is not important. Where the bay segments rise together, it is preferred that the brush elements are longitudinally aligned as described above.

The bristle arrangement can vary considerably. Each bristle is preferably thicker in diameter than the cards being separated and, in general, a thickness of from 5 to 25 mils will suffice. The number of bristles in a segment is preferably chosen such that if all of the bristles of an element extend downwardly between the adjacent cards, the cards would not jamb in the device. This will depend, of course, on the number of cards in the device. However, considering a given bay segment, the free space between edge-aligned parallel cards arranged as shown in the drawings will generally be about 50 to 85 percent, preferably 70 to 80 percent, of the bay width. Thus, the brush elements are such that the number of bristles in contact with the cards at any given time, is preferably not greater than about 50 to 85 percent, preferably 70 to 80 percent, of the bay width. The thickness of an element, that is the circumferential distance between the leading and trailing edge of the brush element, can vary widely. However, the total thickness of all of the brushes is preferably less than one half of the circumference of the brush surface in order to provide effective vibrating action.

What is claimed is:

1. In a method of separating selected cards from a plurality of edge-aligned, vertically oriented cards wherein selected cards are moved relative to the remaining, rejected, sheets to effect separation, the improvement which comprises facilitating said separation by contacting the edges of edge-aligned cards having adjacent cards supporting one another in vertical orientation with a moving brush, said brush including bristles which are sufficiently flexible to deflect upon striking said edges and sufficiently stiff to pass into the space between adjacent sheets to pass between adjacent cards to facilitate separation thereof, said brush being moved such that the bristles move lengthwise of said cards.

2. An improved card separating device according to claim 1 wherein said brush comprises an arbor member defining at least one rotatable segment, at least one brush element located in each segment, and each brush element comprising a plurality of bristles extending

outward of said segment.

3. An improved card separating device according to claim 2 wherein said brush element extends circumferentially about said segment.

4. An improved card separating device according to claim 3 wherein said brush element extends spirally about the entire circumference of said segment.

5. An improved card separating device according to claim 2 wherein said brush element extends longitudinally of said segment.

6. An improved card separating device according to claim 5 wherein said segment includes a plurality of circumferentially spaced brush elements.

7. An improved card separating device according to claim 6 wherein each brush element extends less than the full longitudinal length of the bay segment and each brush element is partially displaced longitudinally of the bay segment with respect to each adjacent brush element with longitudinal overlap between adjacent brush elements.

8. An improved card separating device according to claim 6 wherein said arbor comprises a plurality of said segments and wherein each segment comprises at least three brush elements equally spaced about the circumference thereof, each brush element of a segment being in longitudinal alignment with a brush element of all other segments.

9. An improved card separating device according to claim 6 wherein said arbor is moveably supported for motion relative to said aligned edges to permit rise motion of the arbor occasioned by intermittent contact between the edges and the brush elements, the circumferential distance separating adjacent brush elements being such that the time interval between successive intermittent contacts between brush elements and said aligned edges upon rotation of said bay segment at operating speed is not greater than the time interval required for rise motion of the arbor.

10. In a device for separating selected cards from a plurality of edge-aligned, vertically oriented, cards including at least one storage bay for holding a plurality of edge-aligned cards with adjacent cards supporting one another in vertical orientation, means for moving certain selected cards relative to the remaining, rejected cards to effect separation thereof: the improvement wherein said device includes brush means to facilitate separation of said cards, said brush means comprising a base member having bristles extending outwardly therefrom, said base member being positioned adjacent to aligned edges of said cards with the bristles of said brush member being engageable with the aligned edges of the cards in said bay, and means connected to said base member for moving the brush bristles in engagement with said aligned edges to facilitate card separation, said bristles being sufficiently flexible to deflect upon striking said card edges and sufficiently stiff to enter into the space between adjacent cards to pass between adjacent cards to facilitate separation thereof.
